INSULATIVE ROLLER BEARING PILLOW BLOCK

James B. Mallard, 3800 W. Alabama, Houston, Tex.

Filed Aug. 2, 1960, Ser. No. 61,600

Term of patent 3½ years

(Cl. D55—1)

FIG. 1 is a top perspective view of an insulative roller bearing pillow block, embodying my new design;

FIG. 2 is a side elevational view thereof taken from the right of FIG. 1, the opposite side being identical; and

FIG. 3 is a side elevational view thereof taken from the left of FIG. 1, the opposite side being identical.

The bottom is substantially plain as indicated in FIGS. 2 and 3.

I claim:

The ornamental design for an insulative roller bearing pillow block, as shown and described.
